CLAIM

The ornamental design for a combined ball holder and set of game balls, as shown and described.

DESCRIPTION

FIG. 1 is a side perspective view of a combined ball holder and set of game balls as viewed from the top and one end;

FIG. 2 is a perspective view of the opposite side thereof as viewed from the bottom and opposite end;

FIG. 3 is an elevational view of one end thereof; and
FIG. 4 is an elevational view of the opposite end thereof.

FIG. 1

FIG. 2

FIG. 3

FIG. 4
